DESIGN FOR AN INCENSE VAPORIZER

Satish Chandra Ghose, Chicago, Ill.

Application November 3, 1938, Serial No. 80,849

Term of patent 7 years

To all whom it may concern:

Be it known that I, Satish Chandra Ghose, a subject of the King of Great Britain, residing at Chicago, in the county of Cook and State of Illinois, have invented a new, original, and ornamental Design for an Incense Vaporizer, of which the following is a specification, reference being made to the accompanying drawing, forming a part thereof.

On the drawing,
Fig. 1 is a front perspective view of an incense vaporizer showing my new design;

Fig. 2 is a side view thereof; and
Fig. 3 is a top plan view thereof.

I claim:

The ornamental design for an incense vaporizer, as shown.

SATISH CHANDRA GHOSE.
